UNITED STATES PATENT OFFICE.

EDWARD H. DEWSON, OF NEW YORK, N. Y., AND WALTER V. TURNER, OF EDGEWOOD, PENNSYLVANIA, ASSIGNORS TO THE WESTINGHOUSE AIR BRAKE COMPANY, OF WILMERDING, PENNSYLVANIA, A CORPORATION OF PENNSYLVANIA.

ELECTROPNEUMATIC VENT-VALVE DEVICE.

1,131,219.

Specification of Letters Patent.

Patented Mar. 9, 1915.

Original application filed May 9, 1910, Serial No. 560,172. Divided and this application filed June 21, 1912, Serial No. 705,074.

To all whom it may concern:

Be it known that we, EDWARD H. DEWSON and WALTER V. TURNER, citizens of the United States, residents of New York, in the county of New York and State of New York, and Edgewood, in the county of Allegheny and State of Pennsylvania, respectively, have invented a certain new and useful Improvement in Electropneumatic Vent-Valve Devices, of which the following is a specification.

This invention relates to an electro-pneumatic brake apparatus and is a division of application Serial No. 560,172, filed May 9, 1910.

The principal object of our invention is to provide an improved electro-pneumatic train pipe vent valve device.

In the accompanying drawing Figure 1 is a central sectional view of the improved electro-pneumatic train pipe vent valve device embodying our invention and Fig. 2 a diagrammatic view showing the wiring and piping connections for said vent valve device.

According to the construction illustrated, the improved vent valve device may comprise a casing 30 having a piston chamber containing a piston 32, the chamber 31 on one side of the piston being normally open to the train pipe through a passage 33 containing a check valve 34, and passage 35 leading to pipe 36, which is connected to the train pipe 1. The piston is subject on its opposite face to the pressure of a chamber 37 which is preferably connected through a passage 38 with a small reservoir 39, so as to increase the volume of the chamber.

The triple valve on each car preferably communicates with the train pipe by connecting the usual triple valve branch pipe 40 with the passage 35 in the vent valve casing. The piston 32 carries a valve 41 adapted to control communication for venting fluid from passage 35 and the train pipe to a pipe 42 opening into a chamber 43 of a pneumatic switch casing 44.

Mounted within the piston 32 is a piston 45 for controlling communication from the

passage 33 to chamber 31. A passage 46 leads from the chamber 31 to an electro-magnet valve device 47 having a valve 48 adapted to control communication from the passage 46 to an atmospheric exhaust port 49. The valve 48 is normally held closed by a spring 50 and is adapted to be opened by the movement of the armature 51 of an electro-magnet 52.

In the switch casing 44 is a piston chamber 53 containing a piston 54 having a piston stem 55 carrying a movable switch contact 56. One fixed switch contact 59 is connected by a wire 57 with a train wire 58, the latter wire being connected to one terminal of the vent valve magnet 52, and the other fixed contact 60 is connected to ground, so that when the switch is closed the line wire 58 and the magnets 52 are grounded. A spring 61 acts on the piston 54 to normally maintain the switch open. The other terminal of the magnet 52 is connected by a wire 62 to a source of current, such as the third rail or trolley, preferably on each car, a suitable resistance 64 being interposed in the circuit.

When the brake system is charged up, fluid under pressure flows through the passage 35 and a small port 63 in the check valve 34 to passage 33 and thence to chamber 31, and the piston 32 being in its outer position, air flows through a feed groove 65 around the piston, charging the chamber 37 and reservoir 39 to the normal pressure carried in the system. The circuit of the magnet 52 is normally open and the valve 48 is held closed by the spring 50, but upon closing the circuit, the movement of the armature 51 opens the valve 48 and air is vented from chamber 31 through passage 46 to exhaust port 49. The higher pressure in chamber 37 thereupon shifts the piston 32 to its inner seat opening the valve 41. Fluid from the train pipe then flows through passages 35 and 42 to chamber 43 of the switch device 44 and thence through a passage 66 to the upper side of piston 54. Said piston is thus shifted to cause the switch contact 56 to close the circuit across the terminals 59

and 60, so that the train wire 58 is grounded and all the magnets 52 are thereupon energized. In the closed position of the piston 54, a port 67 is open to the space above the piston, so that fluid from the train pipe can escape to an atmospheric exhaust port 68.

Upon a predetermined reduction in train pipe pressure by venting to the exhaust port 68, the spring 61 shifts the piston 54 upwardly, opening the circuit across the terminals 59 and 60. The magnets 52 being thereupon deenergized, the valves 48 are closed, and as the piston 32 is seated, with the feed groove 65 closed, fluid pressure is bottled up in chamber 37. The pressure on the opposite side of piston 32 continues to reduce by flow from chamber 31 past check valve 34 to vent passage 42, an exhaust port 99 opening to passage 66 providing for the release of air when the port 68 is cut off, until the pressure in the chamber 37 acting on a differential area 69 of the piston 45, communication being provided to said area by way of ports 70, together with the train pipe pressure acting within the seated area of said piston 45, is sufficient to overcome the train pipe pressure acting on the outer face of piston 45, then the piston 45 moves from its upper seat, and exposing the full area thereof to the higher pressure of the chamber 37, is instantly seated downwardly, so as to cut off communication from the train pipe passage 38 to chamber 31. It will be noted that a restricted passage 71 is provided through the stem 72 of the piston 32, so that the pressure of fluid flowing from the passage 35 to the passage 42 is supplied to the chamber within the piston 45. The piston 45 being seated downwardly, communication is opened from chamber 37 through ports 70 and the restricted port 71 to passage 42, so that the pressure in chamber 37 now reduces with the train pipe pressure, while the pressure in chamber 31 is bottled up. It will therefore be evident that as soon as the pressure in chamber 37 reduces a certain amount, the pressure in chamber 31 will exceed the pressure in chamber 37 and the piston 32 will thereupon be shifted upwardly to close the valve 41, and cut off the further flow of air from the train pipe. The pressure in the chamber within piston 45 then rapidly drops to atmospheric pressure by flow through the passage 42 and exhaust port 99, and the pressure acting on the lower exposed face of the piston 45 thereupon shifts the piston to its upper seat.

It will now be evident that the vent valve device operates to effect a predetermined reduction in train pipe pressure, the reduction depending upon the relative proportioning of the parts, so that all the triple valves in the train are caused to operate practically simultaneously to produce an

emergency application of the brakes. One of the important features of our invention is that the simultaneous action of all the vent valves in the train may be effected by the action of any one vent valve pneumatically, as by a sudden reduction in train pipe pressure initiated at some point in the train, for example upon a break-in-two, or upon making an emergency reduction in train pipe pressure at the head end of the train by means of the brake valve, the venting of fluid under pressure from chamber 31 being then through passages 33 and 35. The operation of a single vent valve anywhere in the train closes a corresponding switch 56 and thus completes the circuit for all the magnets 52 in the train so that all vent valves are caused to operate simultaneously.

The circuit of the magnets 52 may be closed in various ways, as by means of a conductor's switch 73 on the car, adapted to connect the line wire 58 to ground, or by providing a contact in the brake switch adapted in emergency position to connect the wire 58 to ground.

As an additional safeguard, means may be provided in some cases, whereby the vent valve is operated by the breaking of a normally closed circuit, for example, a magnet 75 having an armature 76 for controlling a valve 77 may have a pipe connection 78 to the passage 46, the opening of the valve 77 being adapted to vent air from passage 46 and chamber 31 to an exhaust port 79. The circuit for magnet 75 is preferably arranged with a wire 80 on the head car connected to a source of current and one terminal of the magnet 75 and a wire 81 connected to the other terminal and extending through the train and including the magnets 75 on the other cars of the train. On the last car the wire 81 is connected to the ground. It is thus seen that the magnets 75 are maintained normally energized and the valves 77 are kept closed by the armature 76. If the wire 81 is broken from any cause, or if there is a failure of current, the magnets 75 are operated and air is vented from the vent valve pistons 32 to effect a sudden reduction in train pipe pressure and an emergency application of the brakes.

Instead of an additional contact in the brake switch, the action of the vent valves may be initiated by connecting the usual exhaust pipe of the brake valve with the chamber 48 of the vent valve switch on the head car, so that in emergency position air exhausted from the train pipe is vented to chamber 48 and thereby the switch 56 on the head car is actuated to ground the vent valve circuit for the train and in this manner effect the simultaneous action of all the vent valves.

If the switch 44 is connected to the ex-

haust pipe of the brake valve, the exhaust of air from the train pipe in making service applications of the brakes is provided for by the port 99, which is made of sufficient size for that purpose. Thus the piston 54 will only be actuated when a sudden reduction in train pipe pressure is made.

Having now described our invention, what we claim as new and desire to secure by Letters Patent, is:—

1. In a fluid pressure brake, the combination with a train pipe and a valve device for controlling the application of the brakes, of a pneumatically operated valve mechanism adapted to effect a reduction in train pipe pressure and electrically controlled means for also operating said valve mechanism.

2. In a fluid pressure brake, the combination with a brake cylinder, train pipe, and means operating upon a reduction in train pipe pressure for effecting an application of the brakes, of a valve mechanism operating upon a sudden reduction in train pipe pressure for locally venting the train pipe and electrically controlled means for also operating said valve mechanism.

3. The combination with an automatic brake apparatus operating upon a reduction in train pipe pressure for effecting an application of the brakes, of a vent valve mechanism adapted to locally vent the train pipe, electrically controlled means for effecting the operation of said vent valve mechanism, and an electric switch device governed by said vent valve mechanism for controlling the electric circuit of said electrically controlled means.

4. In a fluid pressure brake, the combination with a train pipe and brake cylinder, of a vent valve mechanism for locally venting the train pipe, having an electrically controlled device for effecting the operation of the vent valve mechanism, an electric circuit for said electrically controlled device, and an electric switch governed by the vent valve mechanism for controlling said electric circuit.

5. In a fluid pressure brake, the combination with a train pipe, of a vent valve mechanism having a movable abutment normally subject to opposing fluid pressures, one of which is train pipe pressure, and electric means for venting fluid from one side of said abutment to operate said vent valve mechanism and produce a local venting of the train pipe.

6. In a fluid pressure brake, the combination with a train pipe, of a vent valve mechanism adapted upon a sudden reduction in train pipe pressure to effect a local venting of the train pipe, electric means for also operating said vent valve mechanism, and an electric switch device operated by said vent valve mechanism upon venting the train

pipe to close the circuit for said electric means.

7. In a fluid pressure brake, the combination with a train pipe, of a vent valve mechanism operating upon a sudden reduction in train pipe pressure for locally venting the train pipe, electric means for also operating said vent valve mechanism, and an electric switch device operated by the flow of air from the vent valve mechanism upon venting the train pipe for controlling the electric circuit of said electric means.

8. In a fluid pressure brake, the combination with a brake cylinder, train pipe, and valve means for locally venting the train pipe, of electrically controlled means for operating said valve means and an electric switch device for controlling the electric circuit of said electrically controlled means and operating upon an emergency application of the brakes to effect the operation of said electrically controlled means.

9. In a fluid pressure brake, the combination with a train pipe, of a vent valve mechanism comprising a movable abutment normally subject to opposing fluid pressures, a train pipe vent valve operated by said abutment upon a sudden reduction in train pipe pressure for venting air from the train pipe, an electro-magnet and a valve operated thereby for releasing fluid from one side of said abutment to operate the vent valve mechanism, and an electric switch for controlling the electric circuit of said magnet and operated by the flow of air from said vent valve mechanism in venting the train pipe.

10. In a fluid pressure brake, the combination with a train pipe, of a vent valve mechanism adapted to locally vent the train pipe and electrically controlled means adapted either upon opening or closing of an electric circuit to effect the operation of said vent valve mechanism.

11. In a fluid pressure brake, the combination with a train pipe, of a vent valve mechanism for effecting a local venting of the train pipe, electrically controlled means operating upon energization and electrically controlled means operating upon de-energization for operating said vent valve mechanism.

12. In a fluid pressure brake, the combination with a train pipe, of a vent valve mechanism operating upon a sudden reduction in train pipe pressure for effecting a local venting of the train pipe, and electrically controlled means operating either upon the completion of one electric circuit or the breaking of another electric circuit for also effecting the operation of said vent valve mechanism.

13. In a fluid pressure brake, the combination with a brake cylinder, train pipe,

4
and triple valve device operating upon a sudden reduction in train pipe pressure for effecting an emergency application of the brakes, of a valve device adapted upon a sudden reduction in train pipe pressure to effect a local venting of the train pipe, an electrically controlled means for operating said vent valve device, and an electric switch operating upon a sudden reduction in train

pipe pressure for controlling the circuit of 10
said electrically controlled means.

In testimony whereof we have hereunto
set our hands.
